Primary Examiner — R. Johnson(74) *Attorney, Agent, or Firm* — Brett Palmquist; Chau
Palmquist(57) **CLAIM**

The ornamental design for a chair, as shown and described.

DESCRIPTION

FIG. 1 is a perspective view of a chair showing my new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The dot-dashed broken lines in the drawings illustrate a boundary that forms no part of the claimed design. The evenly spaced broken lines illustrate the portions of the chair that form no part of the claim.
